UNITED STATES PATENT OFFICE.

EDWARD L. SIBLEY, 2D, OF BENNINGTON, VERMONT, ASSIGNOR TO EDWARD L. SIBLEY MANUFACTURING COMPANY, INCORPORATED, OF BENNINGTON, VERMONT, A CORPORATION OF VERMONT.

BLANKING-OUT EYELETS.

Application filed September 30, 1921. Serial No. 504,298.

To all whom it may concern:

Be it known that I, EDWARD L. SIBLEY, II, a citizen of the United States, residing at Bennington, in the county of Bennington 5 and State of Vermont, have invented a certain new and useful Improvement in Blanking-Out Eyelets, of which the following is a full, clear, and exact description.

The well known "Challenge" eyelet of 10 the Sibley Patent No. 358,225, dated February 22, 1887, has been manufactured commercially in a somewhat different form from that described in the patent. Ordinarily, instead of having four sections or fingers, 15 as in the patent, it has five sections or fingers, and the blanks have been cut from brass ribbon by means of suitable punch presses.

In this process of manufacture there has 20 been an undue proportion of waste or scrap, in some cases the proportions being three pounds of waste or scrap to two pounds of eyelets out of a five pound ribbon of brass, thus unduly increasing the cost of manufacture. Owing to the star-like or radiate 25 form of the blank, it has been difficult to avoid such waste or scrap, but in accordance with the present invention such waste or scrap has been reduced to a minimum and the output of eyelets proportionately increased. 30

In one form of the present invention, three rows of blanks are cut from a single strip of brass of considerably less width than three times the width of the ordinary ribbon from which a single row has been cut 35 in accordance with the former practice. In other words, the output of eyelets may be tripled in using a ribbon considerably less than three times the width heretofore used 40 in cutting out a single row.

The principle of the present invention is embodied in cutting a plurality of rows of star-shaped or radiate blanks of the character referred to from a ribbon of metal 45 either by alternately running the ribbon through the cutting or punching machine in one direction for one row and then reversing for another and so on for as many rows of blanks as are desired, or by providing a punching machine with punches arranged reversely and running the brass ribbon through once and cutting all of the rows simultaneously, as I will proceed now 50 to explain and finally claim.

In the accompanying drawings illustrating the invention, in the several figures of which like parts are similarly designated, Figure 1 is an elevation of a common form of "Challenge" eyelet, and Fig. 2 is a top plan view thereof, the eyelet in both views being shown greatly enlarged. Fig. 3 is a plan view of the blank used in the construction of such an eyelet as that shown in Figs. 1 and 2, and Fig. 4 is a vertical section of the eyelet taken in the plane of line 4—4 Fig. 2. Fig. 5 is a plan view of a piece of stock, also greatly enlarged, showing the invention applied to cutting or punching out three rows of blanks, such as shown in Fig. 3, either one row at a time or all of the rows simultaneously.

The blank comprises the solid central portion 1, forming the head or leading end 2 of the eyelet, which is forced through the material to be eyeleted, in the well-known way of using "Challenge" eyelets; the radial sections or fingers 3 which form the barrel 4, and the lateral arcuate extensions 5 which form the foot or flange 6 of the eyelet.

These blanks are cut from suitable stock, such as soft drawn brass, in ribbon form. In the present instance, the cutting or punching machine has one cutting element arranged parallel with the length of the ribbon, so that one of the sections or fingers 85 will extend parallel with such length, same being indicated by the cuts 7 in Fig. 5. The stock is run through the press so as to cut a row of blanks from one edge, and as near such edge as possible, as indicated 90 at A; then the ribbon is run through in the opposite direction so as to cut out a row of blanks from the center of the stock, the parallelism of section or finger indicated by cut 7 being preserved but said cut being 95 reversed, as indicated at B; and then the ribbon is run through in the same direction as in making the first row so as to cut a row of blanks from near the opposite edge of the ribbon, as indicated 100 at C. In each instance the material for the sections or fingers is cut from the stock between adjacent sections or fingers. In all of the rows the parallel cuts 7 for one blank extend between adjacent cuts of the next blank, and in row B the cuts for the other sections or fingers extend in between the adjacent cuts of the rows on both sides 105

also. Thus, practically all of the scrap occurs in the edges of the ribbon; but by multiplying the number of rows of cuts the proportion of scrap to blanks is greatly reduced. This is true in a two row ribbon and also in one of three or more rows.

One of the important advantages of the present invention is that a maximum number of star-shaped blanks can be cut from a given square of stock with a minimum of waste, and that the greater the square of stock the greater is the product and the less the scrap. These results are due to the fact that not only do the fingers of the blanks in one row enter the stock between the fingers of adjacent blanks both in front and behind, but other fingers enter the stock between the fingers of blanks in the rows on opposite sides.

While I have described my invention as being carried out by cutting one row of blanks at a time and reversing the stock for each succeeding row, it is within my invention to cut all of the rows simultaneously, as by using a gang press, with the punches arranged so that the cuts will be made between parts as previously explained.

The arrangement of cuts shown is of demonstrated practicability, but variations thereof are considered to be within the principle of the invention and the claims following.

What I claim is:

1. The method of blanking out eyelets having radiate or star-shaped blanks, provided with a plurality of sections or fingers, same consisting in punching a plurality of substantially parallel rows of such blanks with the sections or fingers extending in between the cuts of the sections or fingers of adjacent blanks of the same row and also the parallel row or rows on either side.

2. The method of blanking out eyelets having radiate or star-shaped blanks, pro-

vided with a plurality of sections or fingers, same consisting in punching a plurality of substantially parallel rows of such blanks with one of the sections or fingers extending lengthwise of the stock and into the space between adjacent finger cuts, and the other sections or fingers extending into the spaces between finger cuts in an adjacent row.

3. The method of blanking out eyelets having radiate or star-shaped blanks, provided with a plurality of sections or fingers, same consisting in punching a row of blanks lengthwise of the stock, and then running the stock through the punching machine in the opposite direction and punching out a second row of blanks so that said second row of blanks will be headed in the opposite direction to the first, and repeating these operations for any desired number of rows, the sections or fingers of each row being cut from the stock between adjacent section or finger cuts wherever the sections or fingers alternate.

4. The method of blanking out eyelets having radiate or star-shaped blanks, provided with an uneven number of fingers, same consisting in cutting a longitudinal row of blanks having one of the fingers extending parallel with the stock and between adjacent finger cuts of the next blank, then reversing the stock and cutting a parallel row of blanks with their fingers extending in between the finger cuts of the first row as well as between the finger cuts of the second row, and then repeating as in the first cutting.

In testimony whereof I have hereunto set my hand this 28th day of September A. D. 1921.

EDWARD L. SIBLEY, II.
